UNITED STATES PATENT OFFICE.

AXEL A. STROM, OF CHICAGO, ILLINOIS, ASSIGNOR TO PETTIBONE,
MULLIKEN & COMPANY, OF CHICAGO, ILLINOIS, A CORPORATION
OF ILLINOIS.

RAILWAY-RAIL.

SPECIFICATION forming part of Letters Patent No. 794,955, dated July 18, 1905.

Application filed December 23, 1904. Serial No. 238,099.

To all whom it may concern:

Be it known that I, AXEL A. STROM, a citizen of the United States, residing at Chicago, in the county of Cook and State of Illinois, have invented a new and useful Improvement 5 in Railway-Rails, of which the following is a specification.

My invention relates to an improvement in the structural form of the **T** variety of rails 10 employed in railway-tracks, more particularly in frogs, crossings, and switches therein.

Where, as is the common practice in a railway-frog, the tread-surfaces of the head portions of the wing-rails are of the same cross-sectional dimension as that of the main rails 15 the frog-point and the portions of the wing-rails adjacent thereto are subject to rapid wear from pounding against them of the wheels of the rolling-stock in passing over them, with 20 the effect of shortening accordingly the duration of the life of the frog. This pounding is materially augmented where the wear upon the tread-surfaces of the wheels from rolling upon the relatively narrow tread-surfaces of 25 the heads of the ordinary **T**-rails of the main track grooves the wheel-treads, and thereby forms what is known as the "artificial flange" toward their outer circumferential edges, since the depressions about the wheel-treads cause 30 the wheels to drop in their transition from one to the other of the frog-point and a wing-rail. In the case of railway-crossings this pounding against the ends of the rails where 35 spaces are provided between them at the rail intersections to admit the wheel-flanges also occurs from causes analogous to those explained with relation to railway-frogs, with the same detrimental effect upon the rails, and the same wear takes place on the rails at the 40 switches in a railway-track.

The object of my invention is to reduce in a very material measure the extent of wear referred to by providing the rail employed in a position to be subjected thereto with a tread- 45 surface so expanded as compared with the width of head of the main rail employed as to increase its wearing-surface and to adapt it to take the wheels, however much they may be grooved with wear, without material, if

any, shock or pounding by reason of the wider 50 rail-tread surface relative to the width of wheel-tread, whereby it will tend to contact with the wheel-tread on both sides of any circumferential groove therein. To this end I expand the wearing-surface of the rail by increasing 55 the transverse thickness of the head portion and also of the web and base or flange of a part or section thereof entirely and uniformly toward one side thereof to serve as the outer side and reducing the parts of the rail 60 toward one or each end to the cross-sectional dimensions of the main rail or rails with which the expanded rail must be spliced, thereby to cause the end or ends of the expanded rail to register as to its base, web, and flange, respectively, with the corresponding parts of 65 the main rail or rails with which it is to be spliced.

In the accompanying drawings, Figure 1 is a broken plan view of a rail of my improved 70 construction having the expanded portion or section between reduced ends; Fig. 2, a similar view of the same, but with the expanded section extending to one extreme end of the rail; Fig. 3, a view in side elevation of a broken 75 end portion of the rail, showing its expanded and reduced portions; Fig. 4, a section taken at the line 4 on Figs. 1 and 2 and viewed in the direction of the arrow; and Fig. 5, a section taken at the line 5 on Figs. 1 and 2 and 80 viewed in the direction of the arrow, with the width of the reduced end portion indicated by a dotted representation.

A is a rail of the **T** variety, comprising a base or flange *a*, a web *b*, and a head *c*. In 85 the manufacture of this rail a desired length of section thereof is expanded as to its head, web, and base entirely toward one side of the rail, as shown, forming its outer side in use, and thereby leaving the opposite or gage side 90 straight to align with the main rails, with which the improved rail is to be used, and thus maintain the gage-line. Toward one end, as in Fig. 2, or toward each end, as in Fig. 1, the rail A is reduced to the dimensions of the 95 main rail or rails, to which it is to be spliced, in order that the abutting rail ends shall coincide properly and permit the splice-bars em-

ployed to fit in place. The reduction referred to is produced by beveling the thickened parts, as shown at $a' b' c'$, to the required extent to narrow the rail from the outer end of the 5 bevel to the rail end to conform to the dimensions of the respective main-line rail. Thus the desired increase of wearing-surface is attained in the rail A without causing it to interfere with the gage-line of a track containing it, and by expanding it as to its flange and 10 web portions as well as its head portion stability of the rail is assured.

What I claim as new, and desire to secure by Letters Patent, is—

15 1. As a new article of manufacture, a railway-rail of the T variety, having a longitudinal section expanded, as to its head, web and base, entirely toward one side of the rail, and reduced toward an end of the rail to match a 20 main rail to be spliced thereto, substantially as and for the purpose set forth.

2. As a new article of manufacture, a railway-rail of the T variety, having a section between its ends expanded, as to its head, web 25 and base, entirely toward one side of the rail, and having reduced end sections adapted to

match with main rails to be spliced thereto, substantially as and for the purpose set forth.

3. As a new article of manufacture, a railway-rail of the T variety, having its head, web 30 and base, throughout a longitudinal section of the rail, expanded entirely toward one side thereof and reduced toward an end of said rail to match a rail to be spliced thereto, with a beveled section on said side extending between 35 said expanded section and said reduced section, substantially as and for the purpose set forth.

4. As a new article of manufacture, a railway-rail of the T variety, having a section of its head, web and base between the rail ends, 40 expanded entirely toward one side of the rail and reduced from said expanded section toward both ends to match with main rails to be spliced thereto, with beveled sections on said side extending between said expanded 45 and reduced sections, substantially as and for the purpose set forth.
